US00D379122S

United States Patent [19]

Wolff

[11] Patent Number: Des. 379,122

[45] Date of Patent: May 13, 1997

[54] STORAGE CONTAINER

- [75] Inventor: Stacy L. Wolff, Houston, Tex.
- [73] Assignee: Rubbermaid Incorporated, Wooster, Ohio
- [] Term: 14 Years
- [21] Appl. No.: 54,543
- [22] Filed: May 16, 1996
- [51] LOC (6) Cl. 03-01
- [52] U.S. Cl. D3/312
- [58] Field of Search .... D3/304-314; D9/414, D9/424, 425, 430-432; 206/503-507, 509, 510, 514, 515, 518, 499; 220/674, 675, 752, DIG. 12, DIG. 14
